SEWING MACHINE

Hans Hacklander, Linden, N. J., and George Sauer, Berwyn, Ill., assignors to Union Special Machine Company, Chicago, Ill., a corporation of Illinois

Application June 22, 1937, Serial No. 149,595

3 Claims. (Cl. 112—63)

This invention relates to sewing machines; and it has reference more especially to feed-off-the-arm sewing machines of the kind typified in U. S. Patent No. 1,741,095, granted to Norman V. Christensen and Harold J. Le Vesconte on December 24, 1929 and in U. S. Patent No. 1,773,028, granted to Norman V. Christensen and Walter M. Hanneken on August 12, 1930.

In machines of the type specifically referred to as heretofore constructed, parts such as thread tensioning and take up devices and means for controlling the tensioning devices and the presser foot were exposed exteriorly of the machine frame where they were in the way and thus apt to be injured themselves or to cause injury to the operatives of the machines.

One aim of our invention is to preclude the contingencies mentioned by providing as hereinafter more fully disclosed for the accommodation of the thread tensioning and take up devices and the presser foot lifting means within the frame of the machine, together with the mechanism for actuating the needle bar, the complementary stitch-forming means and the feed means, so that all the parts of the machine are completely enclosed except for the needle or needles, the presser foot and the drive wheel.

Our invention is also directed toward the provision of an improved and simplified form of control means for the tensioning devices and the presser foot which adapts itself to being readily enclosed with other mechanisms within the machine frame.

Other objects and attendant advantages will appear from the following detailed description of the attached drawings, wherein

Fig. I shows, in plan, a feed-off-the-arm machine conveniently embodying the present improvements.

Fig. II is a fragmentary view of the machine in plan, drawn to a larger scale, with the top cover members of the hollow machine frame removed and with portions of the frame broken out and sectioned to expose some of the mechanism at the interior.

Fig. III is a side elevation of the machine with portions of the frame broken out and sectioned.

Fig. IV is a longitudinal sectional view through the work supporting arm of the machine.

Fig. V is a view of the work supporting arm partly in plan with the cover plates removed, and partly in horizontal section taken as indicated by the arrows V—V in Fig. IV.

Figs. VI and VII are fragmentary detail sectional views taken as indicated respectively by

the arrows VI—VI and VII—VII in Figs. I and II; and

Fig. VIII is a fragmentary sectional view on an enlarged scale showing the details of one of the tensioning devices of the machine.

The sewing machine herein illustrated for convenience of exemplifying our invention has a frame 1 with a tubular longitudinal portion 2 which is supported at an elevation by a base 3 integrally formed therewith. Joined by a vertical tubular portion 4 to one end of the tubular longitudinal portion 2 of the machine frame is a hollow work supporting arm 5 whereof the free end underreaches a hollow laterally projecting head 6 near the corresponding end of said longitudinal portion. Confined to vertical reciprocation in the head 6 is a needle bar 7 which, at its lower end, carries a pair of needles 8. As shown in Figs. II and VI, the needle bar 7 is reciprocated through a link 9 from a balanced crank element 10 at the front end of a transverse shaft 11 journaled within the head. By means of a pair of miter gears 12 and 13 running in a closed oil compartment 14 interiorly of the machine frame 1, the transverse shaft 11 is driven from the main shaft 15 of the machine. As shown in Figs. I—III, the main shaft 15 is journaled in suitably spaced bearings 16, 17, 18 and 19 within the elevated tubular portion 2 of the machine frame 1, and which is provided at its protruding end with a combined hand and belt wheel 20 so that it may be driven either manually or by power.

Disposed within the hollow of the work supporting arm 5 (see Figs. IV and V) is a feed bar 21 carrying at its front end a feed dog 22 whereof the teeth project upward through an opening 23 in the throat plate 24 of the machine. Adjacent its forward end, the feed bar 21 is pivotally supported by the upper end of vertical links 25 whereof the lower ends are pivotally connected to the horizontal arm 26 of a bell crank lever 27 fulcrumed on a pin 28 extending crosswise of the work supporting arm 5. At its rear end, the feed bar 21 is pivotally connected to the pendant arm 29 of another bell crank member 30 fulcrumed on a fixed cross pin 31 at the rear end of the work supporting arm 5, the horizontal arm 32 of the bell crank member being coupled by means of a vertical link rod 33 with an eccentric actuator 34 on the main shaft 15, see Figs. I—III. By the arrangement just described, back and forth or feed movements are continuously imparted to the feed dog 21 incident to rotation of the drive shaft 15.

The feed bar 21 derives its lift movement from

another eccentric actuator 35 on the drive shaft 15 whose movements are transmitted, through a strap rod 36 to another bell crank member 37 within the hollow of the work supporting arm 5 5 which is in turn connected to said feed bar by a horizontal link 38.

Arranged to cooperate with the needles 8 below the throat plate 24 are loopers, whereof one is shown at 39, which are connected to the front 10 end of a horizontal shaft 40 journaled interiorly of the work supporting arm 5 below the feed bar 21 with capacity for both rocking and endwise movement. Rocking movements are imparted to the looper shaft 40 from a third rotary eccentric 15 actuator 41 on the drive shaft 15 through intermediate connections including a vertical strap rod 42 and a crank arm 43 on said shaft to which said strap rod is connected at its lower end. Endwise movements of the looper shaft 40 are derived 20 from a fourth eccentric actuator 45 on the drive shaft 15 through a vertical strap link 46 which at its lower end is connected to another bell crank lever 47 which is independently rockable on the fulcrum pin 31 hereinbefore mentioned and which 25 is in turn connected by a short link 48 with a collar 49 on the looper shaft 40. The collar 49 is rotatively free on the looper shaft 40 but held against axial movement thereon between the boss of the crank arm and a backing collar 50 fixed on 30 said shaft. Cooperative with the looper 39 is a spreader 51 which is secured to the front end of a sleeve 52 surrounding the greater portion of the looper shaft 40. The sleeve 52 is oscillated from a fifth eccentric actuator 53 on the drive shaft 35 15 through an associated strap link 54, whereof the lower end is connected to a bell crank arm 55 affixed to the rear end of said sleeve. It is to be particularly noted that the five strap rods 33, 36, 42, 46 and 54 all extend through the hollow 40 vertical connecting portion of the machine frame between the elevated longitudinal portion 2 and the work supporting arm 5.

Confined to vertical reciprocation in the head 6 independently of the needle bar 1 is a presser bar 45 56 (see Figs. II, III and VI), said bar having guidance in bushings 57 and 58 respectively secured in the bottom of the head and in a boss 59 or lug within said head. At its lower end, the presser bar 56 carries a presser foot 60 which is 50 held in yielding contact with the fabric being sewed during the operation of the machine by a double leaf spring 61 (Figs. II and VI) enclosed within the hollow of the machine frame. As shown, the leaf spring 61 is anchored by a stud 55 62 projecting upward from a lug 63 within the machine frame and extends forwardly over the main shaft 15 and into the hollow of the head 6. At its outer end the spring 61 is clevised to straddle an inverted stirrup member 64 bearing on the round- 60 ed upper end 65 of the presser bar 56. The pressure of the spring 61 is regulatable by a thumb screw 66, the threaded shank of which passes through a removable section or cover member 67 of the machine frame. The presser bar 56 is 65 strained against rotation through engagement of the projection 68 of a collar 69 thereon (see Figs. II and III) with a vertically slotted guide plate 70 secured within the head 6.

Within the hollow elevated portion of the machine frame 1 (Figs. II and III), a central chamber 71 is set apart and isolated from two end chambers respectively containing the needle operating and the feed operating mechanisms, by a pair of spaced cross partitions 72 and 73. As 75 shown in Figs. II and VII, the chamber 71 is

extended or offset laterally to one side of the shaft 15 so as to provide space for the accommodation of tensioning devices 74, 74 and 75, 75 respectively for the needle and the looper threads T, T and T', T'. Each of these tensioning devices, see Fig. 5 VIII, includes a pair of disks 76, 77 between which the thread passes, said disks being axially apertured to engage an upright stud 78 whereof the lower threaded end is screwed into a tapped boss 79 integrally formed with a shelf 80 to one side of 10 the shaft 15 within the chamber 71. Clamped between a circumferential flange 81 on the stud 78 and the top of the boss 79 is a plate 82 having spaced upstanding fingers 83, 84 at opposite ends thereof for guiding the thread. By means of a 15 helical compression spring 85 surrounding the stud 78, the upper disk 76 is yieldingly urged toward the lower disk 77 so that restraint is normally imposed upon the thread to tension it as it passes between said disks. The pressure of the 20 spring 85 is regulatable to vary the tension on the thread by means of a thumb nut 86 engaging screw threads on the upper part of the stud 78. Secured to that portion of the drive shaft 15 extending through the chamber 71 is a pair of rotary 25 take ups 87, 88, respectively for the needle and looper threads T, T and T', T'. En route from suitable individual sources of supply (not shown) the threads T, T and T', T' respectively enter the compartment 71 through tubular ingress 30 guides 89, 89 and 90, 90 in one side wall of the elevated portion 2 of the machine frame and leave it by way of tubular guides 91, 92 in the other side wall of said elevated frame portion—all as shown in Figs. II, and VII. Within the chamber 35 71, the threads T, T' respectively pass first to the tension devices 74, 75 and thence through fixed guides shown at 93, 94 to the rotary take ups 87, 88 on the main shaft 15. After emerging from the chamber 71 through the guides 91, 92, the 40 threads T, T, T', T' are directed to the needles 8 and the loopers 39 by other suitable guides which are not illustrated in the drawings. The chamber 71 is closed at the top by a cover member 45 95 which is attached along one edge thereof by a hinge connection 96, see Figs. II and III, and which is provided at one or more points, as instanced in Fig. VII, with downwardly extending spring fingers 97 adapted to frictionally engage the inside edges of the access opening of said 50 chamber.

For the purpose of controlling the presser foot 60, we have provided means including a lifting finger 98 which, as shown in Figs. II and VI is fulcrumed on a horizontal pin 99 extending crosswise of the head 6 and which engages the underside of another projection 100 of the collar 69 hereinbefore mentioned, on the presser bar 56. Secured to a rock shaft 102 journaled within the hollow of the base 3 of the machine frame 1 is a bell crank lever 103 whereof the upwardly extending arm 104 is coupled, by means of a horizontal link 105 overreaching the drive shaft 15 to an upwardly extending arm 106 of the lifting finger 98, the downward angular arm 107 of the bell 60 crank 103 being in turn connected by a chain 108 65 to a foot treadle or the like (not illustrated). Downward pull on the chain 108 will obviously cause counterclockwise movement of the bell crank 103, which movement will be imparted 70 through the link 105 to the finger 98 with resultant lifting of the presser bar 56 to elevate the presser foot 60 above the throat plate 24.

In order that the tension on the needle threads T, T may be relieved concurrently with lifting of 75

the presser foot 60, further provisions have been made according to our invention as follows: From Figs. II, VII and VIII, it will be noted that the rock shaft 102 is disposed to one side of the shaft 15 in parallelism therewith, and that it extends through the portion 72 (which is continued as the side wall of the chamber 72) beneath the bottom of the intermediate chamber 71 where it is formed with an eccentric end portion 110. As shown the eccentric end 110 of the rock shaft 102 is in line with the needle thread tensioning devices 74 and engaged by pins 111 axially within the studs 78 of the said devices. At their upper ends, each pin 111 engages a diametral web portion 112 of the upper disk 76 of the corresponding tensioning device 74, said web extending crosswise of a longitudinal slot 113 in the upper part of the studs 78. Thus incident to rocking movement of the shaft 102 as the presser foot 60 is lifted, the upper disks 76 of the two tensioning devices 74 are raised through the action of the eccentric portion 110 of said shaft upon the pins 111 with resultant release of the drag on the needle threads T, T.

While the machine herein illustrated is arranged for forming two independent rows of stitching, it is evident that the same can be readily adapted, by increasing or decreasing the number of needles and loopers, for the production of single rows of stitches or to form a seam with more than two rows. Or again, it may be arranged to produce a seam with connected multiple rows of stitches such as featured in U. S. Patents Nos. 883,614 and 1,934,328 granted respectively to Stockton Borton on March 31, 1908 and to Charles F. Rubel on November 7, 1933.

From the foregoing, it will be apparent that we have provided a sewing machine having all its parts, except for the needle, presser foot and the drive wheel, enclosed within its frame where they are protected against injury through impact with other objects and where they in turn cannot cause injury to the operatives of the machine.

Having thus described our invention, we claim:

1. In a sewing machine a frame with a work support and with a hollow horizontal portion at an elevation above said support; a shaft extending longitudinally through the elevated portion of the frame; spaced cross partitions affording intermediate bearings for the shaft and subdividing the hollow of the elevated portion into three

aligned isolated chambers whereof the central one is extended or offset laterally to one side of the shaft; needle operating mechanism in one of the end chambers; feed operating mechanism in the other end chamber; thread take up means on the portion of the shaft within the central chamber; and an associated yarn tension means disposed in the lateral offset of said central chamber. 5

2. In a sewing machine a frame with a work support and with a hollow horizontal portion at 10 an elevation above said support; a shaft extending longitudinally through the elevated portion of the frame; spaced cross partitions affording intermediate bearings for the shaft and subdividing the hollow of the elevated portion into three aligned 15 isolated chambers whereof the central one is extended or offset laterally to one side of the shaft; needle operating mechanism in one of the end chambers; feed operating mechanism in the other end chamber; thread take up means on the portion 20 of the shaft within the central chamber; an associated yarn tensioning means disposed in the lateral offset of the central chamber, said means comprising a pair of spring pressed disks between 25 which the thread passes; a rock shaft extending beneath the lateral offset of the central chamber; and a tension releasing member extending down from the disks through the bottom of the lateral offset and actuated from said rock shaft.

3. In a sewing machine a frame with a work support and with a hollow horizontal portion at an elevation above said support; a shaft extending longitudinally through the elevated portion of the frame; spaced cross partitions affording intermediate bearings for the shaft and subdividing 30 the hollow of the elevated portion into three aligned isolated chambers whereof the central one is extended or offset laterally to one side of the shaft; needle operating mechanism in one of the end chambers; feed operating mechanism in the other 35 end chamber; thread take up means on the portion of the shaft within the central chamber; an associated yarn tensioning means disposed in the lateral offset of the central chamber; and a top cover for the central chamber capable of retraction for access to the take up and tensioning 40 means. 45

HANS HACKLANDER.
GEORGE SAUER.
